DESIGN FOR A COMPACT

Nathan K. Morris, Asbury Park, N. J.

Application March 5, 1945, Serial No. 118,274

Term of patent 3½ years

(Cl. D86—10)

To all whom it may concern:

Be it known that I, Nathan K. Morris, a citizen of the United States, residing at Asbury Park, county of Monmouth, and State of New Jersey, have invented a new, original, and ornamental Design for Compact, of which the following is a specification, reference being had to the accompanying drawing, forming a part thereof.

I claim:

The ornamental design for a compact, as shown.

NATHAN K. MORRIS.
